DISPENSER FOR HAIRDRESSING LIQUIDS

Duane V. McConnochie, Coral Gables, Fla., assignor to Marion S. Pump, Kalamazoo, Mich.

Application September 24, 1956, Serial No. 611,690

2 Claims. (Cl. 222—207)

This invention relates, in general, to a device for dispensing hairdressing liquids in controllable amounts and, more particularly, to a type thereof whereby said liquids can be removed from a container, raised above the level of said container and then discharged with directional and quantitative control.

It is well known that the dispensing of certain hairdressing liquids, such as a soap solution used to shampoo hair, has in the past been inconvenient, inefficient and generally troublesome. Prior to my invention, it has been standard practice either to pour the liquid soap from a relatively small container into the palm of the hand of the person performing the washing operation, or to provide the container with a cap having a restrictive opening through which the liquid is expelled by a jerking motion of the container. Both of these methods have been unsatisfactory because of the mess which they create, because of the inability to control accurately either the direction or quantity of the liquid which ultimately reaches the hair, and because they necessitate the frequent transfer of the liquid soap from the relatively large containers, in which it is delivered to the place of use, into much smaller containers, which can be conveniently handled by the operator. Furthermore, neither method is able to deposit the liquid soap close to the scalp.

Accordingly, a primary object of this invention is the provision of a liquid dispenser, whereby a hairdressing liquid, such as a soap solution, can be removed from a relatively large container, raised to a level above said container and positively dispensed in controllable amounts at points spaced a substantial distance from said container, without creating the mess normally incident to such an operation, and whereby the most efficient and effective use can be made of the solution dispensed.

A further object of this invention is the provision of a dispenser, as aforesaid, which provides positive control over the direction of the dispensing of the liquid, without the use of power-driven equipment, and which can be arranged to control relatively accurately the amount of liquid dispensed.

A further object of this invention is the provision of a dispenser, as aforesaid, which is relatively inexpensive to fabricate, which is extremely easy to operate, which can be easily adapted to use with any conventional type of container, which is completely foolproof in operation, which can withstand rough treatment, which requires little or no adjustment, and which, under normal operating conditions, requires no maintenance.

Other objects and purposes of this invention will become apparent to persons familiar with this type of equipment upon reading the following specification and examining the accompanying drawings, in which:

Figure 1 is a broken, side elevational view of an apparatus embodying the invention.

Figure 2 is a sectional view taken along the line II—II of Figure 1 and rotated 90 degrees counterclockwise.

Figure 3 is a sectional view taken along the line III—III of Figure 2.

General description

In order to meet the objects and purposes set forth above, as well as others incidental thereto, I have provided a liquid dispenser 10 (Figures 1 and 2), comprised of a resiliently flexible shell or bulb 11 defining a pressure control chamber 12 connected to, and communicating with, a discharge nozzle 13 at one end and an inlet tube 14 at the other end. Said tube 14 is extendable into a container 15 and is provided with a connector 16 for securing said tube 14 with respect to the container. A discharge check valve assembly 17 is provided in the discharge passageway 18, which extends from the chamber 12 through the discharge nozzle 13. An inlet check valve assembly 19, which may be similar to the discharge check valve assembly 17, is disposed within the inlet passageway 20, which extends from said chamber 12 through the inlet tube 14. Said check valve assemblies 17 and 19 are arranged to permit the flow of liquid from the inlet tube 14 through the chamber 12 and the nozzle 13, said liquid being discharged through the nozzle orifice 21 in a manner discussed in detail hereinafter.

Detailed construction

As shown particularly in Figures 1 and 2, the shell or bulb 11 is fabricated, as by molding, from a conventional, resiliently flexible material, such as rubber, in a somewhat elliptical shape, preferably having a circular cross-section and being of a size which will fit comfortably within the grip of a normal, average, adult hand. The material from which said bulb 11 is fabricated is sufficiently resistive to compression, as by squeezing, that it will tend to return to its normal shape, shown in Figures 1 and 2, with considerable force after it is released from such compression. The ribs 25 placed on, and integral with, the outer surface of the bulb 11 not only tend to provide additional resistance to such compression, but also provide gripping means on the bulb.

The opposite ends of the bulb 11 (Figure 2) are provided with integral, preferably coaxial, tubular extensions 26 and 27. The tubular inlet extension 26 snugly receives the outlet end 39 of the cylindrical valve body 28, which is part of the inlet check valve assembly 19. The valve body 28 (Figure 3) is preferably elongated and cylindrical in shape and has a coaxial valve passageway 29 extending therethrough. The outlet end 31 of the valve passageway 29 is of enlarged diameter, whereby a conical valve seat 32 is provided within the valve body 28. A valve 33, having a stem 34 and a conical valve head 35, is disposed within the passageway 29 so that the conical surface of said valve head 35 engages the valve seat 32 in a substantially conventional manner. Resilient means, such as the spiral valve spring 36, is disposed within the enlarged portion 31 of said passageway 29 and bears against the valve head 35. Said spring 36 is held under compression within said end portion 31 and against the valve head 35 by means of the hooks 37 and 38, which extend inwardly from the outlet end 39 of the valve body 28. In this particular embodiment, said hooks 37 and 38 are formed by bending portions of the outlet end 39 of said valve body 28 radially inwardly toward each other.

The outer surface of the valve body 28 (Figures 2 and 3) is provided with an annular flange 41 substantially midway between the axial ends thereof, one side of said flange being engaged by the adjacent end of the inlet extension 26 when the outlet end 39 of the valve body 28 is disposed within said inlet extension. The other side of said flange 41 is engaged by the adjacent end of the inlet tube 14 when the inlet end 30 of said

valve body 28 is disposed within said inlet tube 14. A pair of spaced, gripping rings 42 encircle, and are integral with, said valve body 28 on both sides of the flange 41 for the purpose of preventing disengagement of said valve body 28 from its position within the inlet extension 26 of the inlet tube 14. The valve spring 36 is preferably selected so that it will normally hold the valve 33 snugly against the valve seat 32 until there is a material pressure differential on opposite, axial sides of the valve 33. However, said spring 36 is also selected so that the pressure decrease created in the chamber 12, as the bulb 11 moves from a compressed position to its normal extended position, will be considerably more than enough to compress said spring 36 as the valve head 35 is drawn away from the valve seat 32.

The discharge check valve assembly 17 (Figure 2) is comprised of a valve body 45, which may be, and preferably is, substantially identical with the valve body 28 of the inlet check valve assembly 19. The inlet end 46 of the valve body 45 is snugly received within the discharge extension 27 on the bulb 11, in a manner similar to that in which the outlet end 39 of the valve body 28 is received into the inlet extension 26. The outlet end 47 of the valve body 45 is snugly received within the discharge nozzle 13. The discharge valve body 45 has a valve passageway 48 and a valve seat 49, in which a valve 51 is normally held in the closed position by means of a spiral valve spring 52, in substantially the same manner set forth hereinabove with respect to the inlet check valve assembly 19. Since the valve assemblies 17 and 19 are substantially identical in this particular embodiment, further detailed description of the discharge check valve assembly 17 is believed unnecessary.

It has been found advantageous to provide a valve spring 52 in the discharge check valve assembly 17 of somewhat greater strength than that of the valve spring 36 in the inlet valve assembly 19, in order to prevent accidental leakage through the discharge orifice 21 in said nozzle 13. The inlet valve spring 36 requires only enough strength to positively close the valve 33. However, selection of springs for use in the valve assemblies 17 and 19 is largely a matter of choice and will depend considerably upon the particular application.

The portion 53 of the inlet tube 14 adjacent to the bulb 11 is preferably flexible, thereby providing substantial freedom in the manipulation of the bulb 11. The portion 54 of said tube 14 remote from the bulb 11 is preferably in the form of a relatively stiff pipe. In this particular embodiment, the connector 16 for securing the tube 14 with respect to the container 15 includes a cylindrical cap 55 having a central opening 58 therein, in which a sealing grommet 56 is snugly disposed. The pipe 54 slidably, but snugly, extends through the opening 57 in the grommet 56, whereby the amount of said pipe 54 disposed within the container 15 may be easily and quickly adjusted.

Operation

As indicated by the foregoing description, operation of the dispensing device 10 is preceded by mounting the connector 16 upon the container 15, so that the stiff pipe 54 of the inlet tube 14 extends into the liquid disposed within the container 15. In this particular embodiment, the connector 16 includes a cap 55, which has a vent opening 59 and is securable to the neck of the container 15. Proper adjustment of the pipe 54 with respect to the container 15 may be obtained simply by sliding said pipe upwardly or downwardly through the opening 57 in the sealing grommet 56. The dispensing device 10 is now ready for operation.

Operation of the dispenser is commenced by moving the liquid from the container 15 up through the inlet tube 14 and into the pressure control chamber 12 within the bulb 11. This is accomplished by a series of compressions, and then releases, of the bulb 11. Each such

compression increases the pressure within the pressure control chamber 12, thereby expelling the air in said chamber through the discharge passageway 18 by opening the valve 51, while compressing the valve spring 52. This air is unable to pass through the inlet passageway 20 because it tends to urge the valve 33 more firmly into the closed position.

When the compression force on the bulb 11 is released, the bulb immediately moves toward its normal expanded position, thereby creating a decrease in pressure within the pressure control chamber 12. This permits the discharge valve spring 52 to return the valve 51 to its closed position and, at the same time, opens the inlet valve 33, while compressing the inlet valve spring 36. The decrease in pressure within the pressure control chamber 12 also draws the liquid within the container 15 at least partially through the inlet tube 14 toward the pressure control chamber 12. When the bulb 11 reaches its normal extended position, a combination of the pressure head within the inlet tube 14 and the action of the valve spring 36 causes the inlet valve 33 to close, thereby preventing the liquid within the tube 14 from returning to the container 15.

Each succeeding compression and release of the bulb 11 causes the liquid to move a further distance through the inlet tube 14, until it finally reaches the pressure control chamber 12. When said liquid reaches said chamber 12, further compressions of the bulb 11 will be accompanied by a discharge of the liquid through the orifice 21 in the nozzle 13. By holding the bulb 11 so that the nozzle 13 points upwardly, substantially all of the air disposed within the chamber 12 can be expelled before the liquid is discharged therefrom. The force with which the liquid is expelled is controlled by the rate of compression and, therefore, can be varied from a penetrating stream to a dribble.

Control of the amount of liquid discharged from the chamber 12 with each compression of the bulb 11 can be effected by carefully selecting for a given service the size of the chamber 12, and then substantially completely collapsing the bulb 11 with each operation thereof. Alternatively, the extent to which the bulb 11 is compressed can be manually controlled with reasonable accuracy after some experience, without completely collapsing the bulb. As mentioned above, appropriate selection of a valve spring 52 will prevent accidental unseating of the valve 51 and consequential leakage. The difference between the pressure against the inner end of the valve 51, due to the weight of the liquid thereagainst, even when said bulb 11 is a substantial distance below the container 15, is relatively small by comparison to the pressure which may be imposed upon said valve 51 by compressing the bulb 11, even when such compression is effected by a person having a relatively weak grip. Thus, the valve spring 52 can be made adequately strong to prevent said leakage, without impeding in any material amount the discharging of the liquid through the discharge valve assembly 17 when the bulb 11 is compressed. On the other hand, the valve spring 36 need only be strong enough to provide a positive seating of the inlet valve 33, whereby to prevent siphoning from the pressure chamber 12 back into the container 15.

After the container 15 has been emptied, the dispensing device 10 can be quickly removed from the container 15 and either placed on another full container or replaced upon the first container after it is refilled. After the dispensing device 10 is connected to the fresh supply of liquid, said liquid can again be moved up through the tube 14 and into the chamber 12, in substantially the same manner set forth hereinabove.

Although a particular, preferred embodiment of the invention has been disclosed in detail hereinabove for illustrative purposes, it will be understood that variations or modifications thereof, which do not depart from the

scope of such disclosure, are fully contemplated unless specifically stated to the contrary in the appended claims.

I claim:

1. A device for dispensing hairdressing liquids from a container in carefully controllable amounts comprising: an elongated manually compressible and resiliently flexible shell defining a liquid chamber, said shell being capable of fitting comfortably into the grasp of an average normal adult hand and having gripping means on the exterior surface thereof; a first integral tubular extension at one end of said shell defining an inlet passageway communicating with said chamber; a second integral tubular extension at the other end of said shell defining an outlet passageway communicating with said chamber; a pair of substantially similar check valve assemblies, each valve assembly including an elongated tubular and one piece body member having an integral annular and outwardly extending flange approximately midway between the ends thereof, a coaxial passageway therethrough, an annular valve seat in said passageway facing one end thereof, a valve engageable with said seat, a pair of elements integral with said body member and extending into said passageway near said one end thereof and spaced from said seat, a valve spring held under continuous compression between said elements and said valve, and gripping ridges integral with and encircling said body member on both sides of said flange, one end of one valve assembly being removably and snugly insertable into the inlet passageway up to said flange and sensed to prevent the flow of liquids out of said chamber, and one end of the other of said valve assemblies being removably and snugly insertable into the outlet passageway up to said flange and sensed to prevent flow of liquid into said chamber; an elongated inlet tube connectable at one end with said container, its other end being removably and firmly sleeved upon the other end of said one valve assembly up to the flange thereon; and a short outlet nozzle removably and firmly sleeved upon the other end of the other said valve assembly up to the flange thereon; the size of said chamber and the flexibility of said shell being such that a normal manual compression of said shell discharges from said nozzle a selected amount of fluid from said chamber and release of said shell draws said amount into said chamber from said container.

2. A device for dispensing hairdressing liquids from a container in carefully controllable amounts comprising: an elongated manually compressible and resiliently flex-

ible shell defining a liquid chamber, said shell being capable of fitting comfortably into the grasp of an average, normal adult hand; a first integral tubular extension at one end of said shell defining an inlet passageway communicating with said chamber; a second integral tubular extension at the other end of said shell defining an outlet passageway communicating with said chamber; a pair of substantially similar check valve assemblies, each valve assembly including an elongated tubular and one piece body member having an integral outwardly extending flange approximately midway between the ends thereof, a coaxial passageway therethrough, an annular valve seat in said passageway facing one end thereof, a valve engageable with said seat, stop means associated with said body member and extending into said passageway near said one end thereof and spaced from said seat, a valve spring held under continuous compression between said stop means and said valve, and gripping means integral with said body member on both sides of said flange, one end of one valve assembly being removably and snugly insertable into the inlet passageway up to said flange and sensed to prevent the flow of liquids out of said chamber, and one end of the other of said valve assemblies being removably and snugly insertable into the outlet passageway up to said flange and sensed to prevent flow of liquid into said chamber; an elongated inlet tube connectible at one end with said container, its other end being removably and firmly sleeved upon the other end of said one valve assembly up to the flange thereon; and a short outlet nozzle removably and firmly sleeved upon the other end of the other said valve assembly up to the flange thereon; the size of said chamber and the flexibility of said shell being such that a normal manual compression of said shell discharges from said nozzle a selected amount of fluid from said chamber and release of said shell draws said amount into said chamber from said container.
